United States Patent Office

Des. 192,961
Patented June 5, 1962

192,961

KNIFE OR SIMILAR ARTICLE

Henry B. Baer, New York, N.Y., assignor to Imperial Knife Company, Inc., New York, N.Y., a corporation of Rhode Island

Filed Dec. 5, 1960, Ser. No. 63,106

Term of patent 14 years

(Cl. D22—3)

FIG. 1 is a bottom view of a knife or similar article showing my new design;

FIG. 2 is a side view thereof as seen from the left of FIG. 1;

FIG. 3 is a top view; and

FIG. 4 is a sectional view of said knife, taken substantially along the line 4—4 of FIG. 2.

I claim:

The ornamental design for a knife or similar article, substantially as shown.
